S. S. GRADY

SOCKET SHELL

Filed June 14, 1923

Stephen S. Grady, INVENTOR
BY
Alvin Johnson, ATTORNEY

UNITED STATES PATENT OFFICE.

STEPHEN S. GRADY, OF NEWTONVILLE, MASSACHUSETTS, ASSIGNOR TO JAY K. COHEN
AND SAMUEL K. COHEN, BOTH OF NEW YORK, N. Y.

SOCKET SHELL.

Application filed June 14, 1923. Serial No. 645,253.

To all whom it may concern:

Be it known that I, STEPHEN S. GRADY, a citizen of the United States, residing at Newtonville, county of Middlesex, and State of Massachusetts, have made certain new and useful Improvements in Socket Shells, of which the following is a specification, taken in connection with the accompanying drawings.

10 This invention relates to electric light socket shells and more particularly to a socket shell for a pull socket.

My invention further relates to a chain guide or horn supported entirely on the shell, free from the insulating porcelains of the pull socket switch mechanism, and held immovably in the chain slot in the shell without assistance from the cap.

20 My invention further relates to such a removable chain guide or horn which is secured to the shell and automatically locked against movement thereon, simply by pressing the chain guide or horn into the chain slot of the shell at substantially right angles to the longitudinal axis of the shell.

25 My invention further relates to certain combinations, articles of manufacture and details of construction, which will be more fully hereinafter described in the specification and pointed out in the claims.

30 In the accompanying drawing showing an illustrative embodiment of my invention and in which the same reference numerals refer to similar parts in the several figures;

35 Fig. 1 is a side elevation of a pull socket employing my invention parts being shown in vertical section for clearer illustration;

Fig. 2 is a horizontal section on the line 2—2 of Fig. 1;

40 Fig. 3 is a side elevation of my improved shell;

Fig. 4 is a side elevation of the usual, or any form of interior porcelains in which, or on which, the pull socket switch (not shown) is mounted;

Fig. 5 is a plan view of my improved chain guide or horn;

Fig. 6 is a horizontal section, similar to Fig. 2, showing a modification in which a stop is mounted on the chain.

Prior to my invention it has been old to use pull sockets and chain guides or horns.

Some of these chain guides or horns were supported on the interior porcelains; others were supported on the shell by more or less

cumbersome constructions involving lugs, tongues and similar locking members, which had to be accurately fitted, and in some cases bent or manipulated after the locking parts were brought into juxtaposition; all of which increased the cost of manufacture. In other cases eyelets have been used as chain guides by dropping them into the chain slot in the shell. In such cases the cap cooperated with the eyelet to prevent it slipping out of the chain slot, there being no other means to prevent the eyelet working up vertically in the chain slot of the shell.

By my invention I support the chain guide or horn entirely on the shell and automatically lock it against movement, simply by pressing it into the chain guide of the shell at substantially right angles to the longitudinal axis of the shell. If desired to disconnect the chain guide or horn at any future time, it is merely necessary to press the horn firmly to one side, to spring the sides of the chain slot in the shell, which will then permit the horn to be withdrawn from the shell.

In the illustrative embodiment of my invention shown in the drawing 1 is an electric pull socket having my shell 2, any suitable form of cap 3, interior porcelains 4 and 5 with which the switch mechanism is mounted (not shown), pull chain 6, and the usual fibre insulation 17.

The metal shell 2 is provided with the usual chain slot 7 to allow the pull chain 6 to pass out of the shell.

In my invention I automatically lock within the chain slot 7 a removable chain guide or horn 8, by simply pressing the guide or horn into the chain slot 7 at right angles to the longitudinal axis of the shell 2.

In the form of my invention shown, I provide the chain slot 7 with an enlarged opening 9, forming locking shoulders 10, 10. I also preferably employ a narrow slot 11, which is practically an extension of the slot 7, but of less width. This slot 11 is preferably employed to permit the portions 12, 12 of the shell 2 to be more easily forced or sprung apart by inserting the expanding portion 13 of the chain guide or horn 8.

This wedge or expanding portion 13 is preferably formed as the frustum of a cone, and is a little larger than the opening 9 in the chain slot 7. It will be clear that as the

conical portion 13 of the chain guide or horn 8 is pressed into the opening 9 the portions 12, 12 of the shell will be forced or sprung apart, the small slot 11, if used as in the preferred construction, assists this spring action of the shell. When the conical member 13 has been forced into the shell so that the walls of the opening 9 register with the kerf 14 in the chain guide or horn 8, the walls of the hole 9 will snap into the kerf 14, and securely hold the chain guide or horn from any movement within the chain slot. It cannot move vertically because the shoulders 10, 10 will prevent such movement, so that it is obvious, from the construction, that it cannot move in any direction. It is, however, removable by applying strong sidewise pressure, which will cause the shell walls of the opening 9 to spring apart sufficient to permit removal of the chain guide or horn when it is desired to remove it.

It will be seen from Fig. 1 that the chain guide or horn 8 is supported entirely on the shell 2 and not on the insulating porcelains 4 and 5. It will also be seen that the cap 3 can be removed without danger of the chain guide or horn 8 dropping, or accidentally working out of the slot 7, for it is supported entirely by the shell 2 without the assistance of the cap 3.

In Figs. 1 and 2 I have shown the pull chain 6 without a stop to limit the retrograde movement of the switch mechanism (not shown), the stop, in such a switch, being a portion of the switch mechanism, (not shown). In some cases I may use the ordinary stop which is an enlarged ball 15, Fig. 6, engaging with the bell 16 of the chain guide or horn.

Having thus described this invention in connection with an illustrative embodiment thereof, to the details of which I do not desire to be limited, what is claimed as new

and what is desired to secure by Letters Patent is set forth in the appended claims. 45

What I claim is:

1. The combination of an electric light pull shell provided with a chain slot having an enlarged circular portion, a removable chain guide or horn provided with a conical wedging surface to cooperate with the circular portion of the chain slot and wedge or spring the walls of the chain slot away from each other and locking surfaces on the chain guide or horn to removably engage with the walls of the chain slot to hold the chain guide or horn immovably on the shell. 50

2. The combination of an electric light pull shell provided with a chain slot having an enlarged circular portion, a removable chain guide or horn provided with a conical wedging surface to cooperate with the circular portion of the chain slot and wedge or spring the walls of the chain slot away from each other, and a kerf on the chain guide or horn to removably engage with the walls of the chain slot to hold the chain guide or horn immovably on the shell. 60

3. An article of manufacture for electric light pull socket comprising a hollow chain guide or horn provided with an exterior wedging surface to wedge apart the sides of the chain slot of a pull socket shell and provided with a kerf to receive the side walls of said chain slot. 75

4. An article of manufacture for electric light pull socket comprising a hollow chain guide or horn provided with an exterior conical surface to wedge apart the sides of the chain slot of a pull socket shell and with a kerf in the conical surface to receive the side walls of said chain slot. 80
